DESIGN FOR A METER PROTECTIVE CASING

Hans A. Bakke, Swampscott, Mass., assignor to
General Electric Company, a corporation of
New York

Application December 28, 1933, Serial No. 50,242

Term of patent 14 years

To all whom it may concern:

Be it known that I, Hans A. Bakke, a citizen of the United States, residing at Swampscott, in the county of Essex, State of Massachusetts, have invented a new, original, and ornamental Design for a Meter Protective Casing, of which the following is a specification, reference being had to the accompanying drawing, forming a part thereof.

The figure is a perspective view of a meter protective casing showing my new design.

I claim:

The ornamental design for a meter protective casing, substantially as shown.

In witness whereof, I have hereunto set my hand.

HANS A. BAKKE.
